UNITED STATES PATENT OFFICE.

GEORGE W. WILLIAMS, OF BROOKLYN, NEW YORK.

MOUTHPIECE.

1,360,844.

Specification of Letters Patent. Patented Nov. 30, 1920.

Application filed July 2, 1920. Serial No. 393,502.

To all whom it may concern:

Be it known that I, GEORGE W. WILLIAMS, a citizen of the United States of America, residing at New York city, borough of Brooklyn, in the county of Kings and State of New York, have invented certain new and useful Improvements in Mouthpieces, of which the following is a specification.

My invention relates to a self-closing mouth piece, and particularly to a mouth piece for bags, or other containers, for tobacco or other comminuted or granular material, and the object of my invention is to provide a self-closing mouth piece through which the material may be readily dispensed, but normally serving to retain the material in the container. The present invention constitutes an improvement upon the construction shown in my prior Patent No. 744,846, dated November 24, 1903.

In the accompanying drawings—

Figure 1 is a broken side elevation of a tobacco bag showing my improved mouth piece applied thereto;

Fig. 2 is a plan of the mouth piece detached;

Fig. 3 is an inverted plan thereof;

Fig. 4 is a section on the line 4—4, Fig. 5;

Fig. 5 is a plan view of the mouth piece opened for dispensing the material; and

Fig. 6 is a section on the line 6—6, Fig. 2.

In the form here shown the present mouth piece comprises a conical neck 7 ellipsoidal in cross section, having at its larger end a flange 8 adapted to lie within the discharge opening of the bag 9. At its opposite end the neck 7 has a pair of lips 10, the meeting faces 11 and 12 of which are straight and of such thickness and contour that in normal position they form a closure for the mouth piece. As will be noted, the lips 10 taper in thickness toward their opposite ends, which are formed on an angle indicated at 13 in Fig. 4 to permit the lips to close completely at the ends of the opening in the normal position of the mouth piece.

On opposite sides of the neck are ribs 14, preferably formed integral with the neck and undercut at 15 at the ends which approach the flange 8. These ribs have the double function of retaining the mouth piece in the discharge opening of the bag, and second of assisting in effecting the automatic closure of the mouth piece after it has been opened. As will be seen in Fig. 4, the draw string 16 at the mouth of the bag

9 is engaged beneath the ribs 14, thus holding the mouth piece in position. If there is a surplus length of the draw string, it may be wound around the neck piece 7 and forced beneath the ribs 14, the latter serving to retain the excess length of the string in out of the way position. The present construction greatly facilitates the adjustment of the mouth piece in the discharge opening 60 of the bag. It is merely necessary to insert the flange 8 of the mouth piece in the opening while the latter is wide open, and then pull the draw string to close the bag opening. Under ordinary circumstances this 65 closes the opening with the bag in the position indicated in dotted lines in Fig. 4 with the margins of the opening resting on the ribs 14. To adjust the draw string beneath the ribs it is merely necessary to tilt the 70 mouth piece first in one direction and then in the other, thereby lifting the ribs 15 above the bag mouth. If there is any slack in the draw string it may now be pulled up and the mouth closed tightly around the 75 neck of the mouth piece as indicated in full lines in Fig. 4. The secondary function of the ribs 14 in assisting the closure of the bag mouth is readily understood. When the neck 7 is deformed by pressure at its opposite ends to separate the lips in the manner indicated in Fig. 5, the sides of the bag neck are opened outwardly, thus bringing the lower ends 17 of the ribs against the bag mouth at a point where it is supported by 80 the flange 8 of the mouth piece. The ribs thus act as resilient struts which assist the normal resiliency of the neck 7 in returning the lips 10 to closed position after deformation.

It will of course be understood that additional ribs may be supplied at the ends of the neck 7 if desired, but I have shown only side ribs since these are sufficient under ordinary circumstances. I have shown the 85 flange 8 separate from the neck 7, but it is perfectly possible, in fact I prefer, to have the entire mouth piece molded in a single operation. The particular form of the ribs 14 may be varied, and the construction as a 90 whole is subject to modification in various ways without departing from what I claim as my invention.

I claim—

1. A self-closing mouth piece of the type 110 described comprising a pair of flexible lips meeting on their opposed faces, a flexible

tube in extension of said lips, flange means on the tube adapted to enter the discharge mouth of an associated container, and longitudinal ribs on the neck and spaced from the flange to accommodate the mouth of said container and to retain the mouth piece in position.

2. A self-closing mouth piece of the type described comprising a pair of flexible lips meeting on their opposed faces, a flexible tube in extension of said lips, flange means on the tube adapted to enter the discharge mouth of an associated container, and longitudinal ribs on the neck and spaced from the flange to accommodate the mouth of said container and to retain the mouth piece in position, said ribs being adapted to bear at their flange ends against the container to form struts which assist in maintaining the lips of the mouth piece normally closed.

3. A self-closing mouth piece of the type described comprising a pair of flexible lips meeting on their opposed faces, a flexible tube in extension of said lips, flange means on the tube adapted to enter the discharge mouth of an associated container, and resilient longitudinal ribs on the neck and spaced from the flange to accommodate the mouth of said container and to retain the mouth piece in position.

4. A self-closing mouth piece of the type described comprising a pair of flexible lips meeting on their opposed faces, a flexible tube in extension of said lips, flange means on the tube adapted to enter the discharge mouth of an associated container, and longitudinal ribs integral with said neck and spaced from the flange to accommodate the

mouth of said container and to retain the mouth piece in position.

5. A self-closing mouth piece of the type described comprising a pair of flexible lips meeting on their opposed faces, a flexible tube in extension of said lips, flange means on the tube adapted to enter the discharge mouth of an associated container, and longitudinal ribs on the neck and spaced from the flange to accommodate the mouth of said container and to retain the mouth piece in position, said ribs being arranged on opposite sides of the neck of the mouth piece.

6. A self-closing mouth piece of the type described comprising a pair of flexible lips meeting on their opposed faces, a flexible tube in extension of said lips, flange means on the tube adapted to enter the discharge mouth of an associated container, and longitudinal ribs on the neck and spaced from the flange to accommodate the mouth of said container and to retain the mouth piece in position, said ribs tapering outwardly from the lips toward the flange.

7. A self-closing mouth piece of the type described comprising a pair of flexible lips meeting on their opposed faces, a flexible tube in extension of said lips, flange means on the tube adapted to enter the discharge mouth of an associated container, and longitudinal ribs on the neck and spaced from the flange to accommodate the mouth of said container and to retain the mouth piece in position, said ribs being undercut at the ends thereof adjacent said flange.

In testimony whereof I have signed my name to this specification.

GEORGE W. WILLIAMS.
